(No Model.)

J. REILLEY.

DIE FOR FORGING TRUCK EQUALIZERS.

No. 387,812.

Patented Aug. 14, 1888.

UNITED STATES PATENT OFFICE.

JAMES REILLEY, OF BUFFALO, NEW YORK, ASSIGNOR OF ONE-HALF TO
THOMAS A. BISSELL, OF SAME PLACE.

DIE FOR FORGING TRUCK-EQUALIZERS.

SPECIFICATION forming part of Letters Patent No. 387,812, dated August 14, 1888.

Application filed May 31, 1888. Serial No. 275,548. (No model.)

To all whom it may concern:

Be it known that I, JAMES REILLEY, of the city of Buffalo, in the county of Erie and State of New York, have invented new and useful 5 Improvements in Dies for Forging Truck-Equalizers, of which the following is a specification.

This invention relates to an improvement in dies for forging the truck-equalizers which connect the axle-boxes of the truck, and which support the springs upon which the car-body rests.

The object of my invention is to construct a pair of dies whereby these truck-equalizers can 15 be produced more expeditiously than heretofore and at the same time be finished in a superior manner.

The invention consists of the improvements which will be hereinafter fully described, and 20 pointed out in the claims.

In the accompanying drawings, Figure 1 is a front elevation of my improved dies. Fig. 2 is a side elevation thereof. Fig. 3 is a rear view of the same. Fig. 4 is a vertical section 25 of the dies in line $x-x$, Fig. 1. Fig. 5 is a top plan view of the lower die. Fig. 6 is a bottom plan view of the punch or upper die. Fig. 7 is a vertical cross-section in line $y-y$, Fig. 4. Fig. 8 is a similar view in line $z-z$, Fig. 3, the 30 section being taken at right angles to Fig. 7. Fig. 9 is a perspective view of one of the equalizers, showing the form thereof previously to being operated upon by the dies. Fig. 10 is a perspective view of the finished equalizer. Fig. 11 is a top plan view of one of the end 35 portions of the equalizer.

Like letters of reference refer to like parts in the several figures.

A represents the body or main portion of 40 the equalizer, the end portions or legs, a a' , of which are bent or curved at an angle to the body portion A and terminate in angular feet b b' , arranged parallel with the body portion A, and whereby the equalizer is secured to 45 the axle-boxes.

In the construction illustrated in the drawings the curve at one end of the equalizer is shorter and more abrupt than the curve at the opposite end of the equalizer, and the leg a' 50 is provided with a shorter foot than the leg a . In trucks having three axle-boxes on each side

two of these equalizers are employed, the long feet of the equalizers being secured to the two outer axle-boxes and the short feet to the intermediate or middle axle-box. When the 55 truck has but two axle-boxes, a single equalizer is used, and both ends thereof are curved correspondingly and have feet of the same size.

C represents the lower stationary die, which is secured to the anvil-block of a steam or 60 power hammer. The die C is provided on its upper side, near one of its lateral edges, with a long convex face, d , for forming the leg a' , having the long curve, and at the base of this convex face with a horizontal rectangular recess or depression, d' , corresponding to the 65 shape of the short foot b' .

e represents a short convex face arranged near the opposite lateral edge of the die C, for forming the leg a , having the short curve, and 70 e' is a horizontal rectangular recess or depression arranged at the base of the convex face e , and having the form of the long foot b .

F represents the punch or upper movable die, which is secured to the head of the power- 75 hammer. The punch F is provided with concave faces f f' , corresponding to the convex faces d e of the lower die, C, and arranged directly above the same, and at the lower end of these concave faces with flat horizontal working-faces g g' . The faces g g' are notched or recessed, as shown at h h' , so that the concave faces f f' will extend to the flat working-faces g g' , the notches h h' fitting over the legs a a' 80 of the equalizer in forging the same.

The lower die, C, is provided between its convex faces d e with a flat horizontal anvil or face, l , and the punch F is formed between its concave faces f f' with a flat projecting face, l' , arranged directly above the anvil or face l . 85

Before being placed between the curved faces of the dies the equalizer is forged between the flat faces l l' to the form shown in Fig. 9, being a straight bar provided at its ends with enlargements or fillets i i' and opposite the point where 90 the abrupt curve is formed with a knee or enlargement, j . The inner edges of the fillets i i' are beveled or inclined, as shown in Fig. 9, so that when the feet b b' are bent into the position shown in Fig. 10 said inclined edges will form 100 a continuation of the upper horizontal edges of the foot and stand parallel with the body A of

the equalizer. The punch and lower die are provided in their adjacent faces, between the concave and convex faces $d e f f'$ and in rear of the flat faces $l l'$, with an opening or recess, 5 m , which enables the punch to clear the inner end of the equalizer when the same is placed between the faces $l l'$. When the equalizer has been forged to the form shown in Fig. 9, the end of the bar, which is to have the short curve and 10 the long foot b , is placed upon the top of the short convex face e of the lower die, the proper position of the bar being determined by marking the same or by means of a gage. The flat face g' of the punch, striking the foot b , gradually bends the unsupported portion of the bar 15 against the convex face e and forms the leg a , and the outer end of the foot, striking the bottom of the recess e' , is gradually bent upwardly at an angle to the leg a until it is squarely 20 seated in said recess. When the leg and foot have been thus bent, the concave face f' of the punch strikes the upper edge of the leg a and finishes the bending of the same. The opposite end of the bar, having the short foot b' , is 25 then placed upon the top of the long convex face d , and the leg a' and its foot are bent in a similar manner.

With my improved dies the equalizers can be produced in much less time than heretofore 30 and by a single heating, and they are more highly finished and rendered more uniform than by making them by hand, as hitherto practiced.

It is obvious that the dies may be divided 35 between the short and long convex and concave faces $d e f f'$ and the dies be attached to separate hammers, in which case one end of the

equalizer is forged upon one hammer and the other end upon the other hammer; but I prefer to use the double die shown in the drawings. 40

When both ends of the equalizer are constructed alike, with feet of the same size and with legs having similar curvatures, only one die is necessary.

I claim as my invention—

1. The combination, with the lower die provided with a convex face and a rectangular recess or depression arranged at the base of said convex face, of a punch or upper die provided with a concave face corresponding to the convex face of the lower die and with a flat working-face arranged above said rectangular recess, substantially as set forth. 45

2. The combination, with the lower die, C, provided with short and long convex faces $d e$, short and long rectangular recesses or depressions $e' d'$, arranged at the lower ends of said convex faces, and with an anvil or flat face, l , arranged between said convex faces, of the punch or upper die, F, provided with short 50 and long concave faces $f f'$, corresponding to the convex faces of the lower die, flat working-faces $g g'$, arranged at the base of said concave faces above the recesses of the lower die, a flat face, l' , arranged between said concave faces 55 above the anvil l of the lower die, and a recess or opening, m , formed in the adjacent faces of the upper and lower dies in rear of the faces $l l'$, substantially as set forth.

Witness my hand this 19th day of May, 1888.
JAMES REILLEY.
